UNITED STATES PATENT OFFICE.

AUGUST A. HARNISCHFEGER, OF NEW YORK, N. Y.

SUSPENSION-CLAMP FOR BACON.

No. 852,951.

Specification of Letters Patent.

Patented May 7, 1907.

Application filed April 25, 1906. Serial No. 313,660.

To all whom it may concern:

Be it known that I, AUGUST A. HARNISCHFEGER, a citizen of the United States, residing in New York, in the borough of Manhattan, county and State of New York, have invented certain new and useful Improvements in Suspension-Clamps for Bacon, of which the following is a specification.

This invention relates to an improved clamp for suspending bacon in the smokehouse.

Heretofore the pieces of bacon were suspended for smoking, by a cord passing through a hole pierced in one end. The suspension-cord produced the deformation in the suspension-end of the piece of bacon, so that when cutting up the same for use this perforated end-piece was usually thrown away as it could not be cut into uniform 20 slices.

The object of this invention is to furnish a suspension-clamp by which the bacon can be suspended without any change in shape and loss of material; and for this purpose the 25 invention consists of a clamp which is formed of two spring-actuated jaws provided with inwardly-bent edges, a hook attached to the upper end of the jaw-connecting piece, and a link moving over the jaws for holding the 30 same in compressed state on the end of the piece of bacon.

The invention consists further of certain details of construction which will be fully described hereinafter and finally pointed out in 35 the claim.

In the accompanying drawings, Figure 1 represents a perspective view of my improved clamp for suspending bacon, showing the same in position for use, Fig. 2 is a side-elevation of the same, drawn on a larger scale, Fig. 3 is an end-elevation, Fig. 4 is a bottom-view, and Fig. 5 is a horizontal section on line 5, 5, Fig. 2.

Similar letters of reference indicate corresponding parts in the different figures of the 45 drawings.

Referring to the drawings, a , a^1 are two jaws which are connected at their upper ends by a transverse piece a^2 , the jaw a being made 50 integral with said connecting-piece a^2 , while the jaw a^1 is hinged to the same, as shown at a^3 . The jaws are provided with narrow shanks a^4 , a^5 and enlarged lower ends a^6 , a^7 , the shanks a^4 , a^5 being preferably made convex so 55 as to increase the strength of the same.

The lower edge of the jaw a^1 is provided with an inwardly-bent sharpened edge b , while the lower end of the jaw a is also bent inwardly and provided with a number of sharp teeth or serrations b^1 . A flat spring e 60 is attached to the shank of the stationary jaw a and presses by its free end on the shank of the movable jaw a^1 so as to force the same in outward direction. Both jaws are perforated by a number of holes h so as to give access of the smoke to the end of the piece of bacon clamped by the jaws. The shanks of the jaws are preferably bent up immediately above said holes, so as to form transverse projections or ridges f for retaining a locking-link d that embraces the shanks of the jaws and holds them firmly in position on the piece of bacon which is to be suspended therefrom. To the transverse head a^2 of the jaws is riveted a hook g , which is located at 70 right angles to the vertical center-plane of the jaws, so as to permit the suspension of the clamp from a rod r . For this purpose the shank of the hook is passed through a transverse slit in the upper part or head of 75 the jaws, and the end bent over to the underside of the same and connected thereto by soldering or otherwise. The hook g is provided at its upper end with an opening o adapted to fit over suitable pins q on the suspension-rod r .

My improved suspension-clamp is applied to the end of the piece of bacon by moving the link in upward direction toward the head of the jaws so that the spring will spread the 90 same to permit the insertion of the piece of bacon, the toothed jaw is pressed firmly into the body of the piece of bacon, and the link permitted to move down over the shanks so as to interlock with opposite projections f 95 and firmly hold the jaws on the bacon. When the bacon is to be removed from the smokehouse, the link is moved in upward direction over the jaws so that the latter spread apart by the tension of the interposed spring and 100 permit the piece of bacon to be removed. It will then only show the small holes that have been made by the teeth of the jaw, but otherwise show no traces of the suspension-clamp on the same. The piece of bacon can thus 105 be cut up for use to the very last piece without any loss.

The entire clamp is preferably made of sheet-steel and galvanized so as to prevent 110 corrosion of the same while in use.

Having thus described my invention, I claim as new and desire to secure by Letters Patent:

A clamp for suspending bacon, comprising a transverse connecting-piece having a jaw made integral therewith, a second jaw hinged to said connecting-piece, the shanks of said jaws being provided with holes and bent up immediately above said holes to form ridges, to a spring interposed between said jaws and

normally spreading the same, and a lip embracing the shanks of said jaws and maintained in position by said ridges.

In testimony, that I claim the foregoing as my invention, I have signed my name in presence of two subscribing witnesses.

AUGUST A. HARNISCHFEGER.
